UNITED STATES PATENT OFFICE.

JOSEPH G. LINDSAY, OF BARTLESVILLE, OKLAHOMA.

CASING-SHOE.

1,363,987.

Specification of Letters Patent.

Patented Dec. 28, 1920.

Application filed May 16, 1918. Serial No. 235,003.

To all whom it may concern:

Be it known that I, JOSEPH G. LINDSAY, a citizen of the United States, residing at Bartlesville, in the county of Washington and State of Oklahoma, have invented certain new and useful Improvements in Cas- 5 ing-Shoes; and I do declare the following to be a full, clear, and exact description of the invention, such as will enable others 10 skilled in the art to which it appertains to make and use the same.

My invention relates to improvements in shoes such as those used on the lower ends of oil well casings and the like to form a tight 15 connection between the casing and the internal ledge formed at the juncture of the two diameters of the well bore. The old form of shoe has been found to be more or less inefficient since it provides no means to prevent the ledge from crumpling and thus the 20 casing is not only permitted to gradually sink, but a tightly packed joint cannot be maintained.

The present invention has for its object to 25 overcome the difficulties above pointed out, by the provision of a simple and inexpensive device, and with this object in view, the invention resides in the novel features of construction hereinafter fully described and 30 claimed, the descriptive matter being supplemented by the accompanying drawing forming a part of this application and in which:

Figure 1 is a vertical section of one form 35 of the invention applied;

Fig. 2 is a side elevation of the device shown in Fig. 1;

Fig. 3 is a duplicate of Fig. 1 but showing a different form of construction; and 40

Fig. 4 is a side elevation of the form of the device shown in Fig. 3.

In the drawings above briefly described, the numeral 1 designates the bore of an oil well or the like which is counterbored at 2 45 to form an internal annular ledge 3 at the juncture of the two well diameters. It is upon this ledge that the shoe 4 of the well casing 5 is supported.

The shoe 4 consists of a tubular body 50 whose upper portion is of sufficient internal diameter to permit the casing 5 to be passed easily into the same for engagement with the internal screw threads 6, whereby to attach the shoe to the casing. At 7, the

55 body of the shoe is shown enlarged although this is not altogether necessary, and the

lower end of the enlargement is beveled upwardly and inwardly to form an annular external shoulder 8 to rest on the ledge 3, thus supporting the casing and forming a 60 seal between the same and the wall of the well bore.

The arrangement so far described is well known to those skilled in the art, but has been found to be more or less inefficient since 65 there is no provision made to prevent crumpling of the ledge 3, and consequent sinkage of the casing, as well as leakage of the joint. I overcome these difficulties however by the addition of a tubular extension 9 on 70 the lower end of the shoe, said extension being preferably formed integrally with the shoe and projecting below the shoulder 8 for snug reception in the smaller diameter of the well bore as seen in Fig. 1. This extension not only prevents caving or crumpling of the ledge 3, but forms an additional seal between the shoe and the wall of the well bore, the advantages of which will be 75 obvious to those skilled in the art. It should 80 be noted that by having the extended lower end portion 9 of this shoe of even diameter throughout its length it may be inserted into the reduced lower portion 1 of the well 2 and will have tight engagement with the 85 walls of the well throughout its entire length thus preventing caving in of the walls of the well at the ledge 3.

In Figs. 3 and 4, the construction of the shoe 4^a is substantially the same as above described, but the shoulder 8^a is not as abrupt as the shoulder 8 and tapers downwardly and inwardly to the extension 9^a. The operation and advantages of this type of the device are identical with those of the form 95 above described, with the exception that the shoulder 8^a will have more of a packing effect on the earth upon which it rests.

From the foregoing, taken in connection with the accompanying drawing, it will be 100 obvious that although I have provided an extremely simple and inexpensive casing shoe, it will possess marked advantages over the devices now commonly used. Since probably the best results are obtained from 105 the details shown and described, they are preferable, but within the scope of the invention as claimed, numerous minor changes may well be made.

I claim:

110 A tubular casing shoe having its walls externally thickened at a point intermediate

its height to provide a supporting collar for engaging the annular supporting ledge in the lower portion of a well, the lower end portion of the shoe providing a sleeve of even external diameter throughout its

walls of the reduced lower end portion of a well below the supporting ledge when the collar is resting upon the ledge.

In testimony whereof I have hereunto set my hand.

JOSEPH G. LINDSAY.
